CONVEYER CONTROL DEVICE

James Vincent Smith, Great Barr, Birmingham, England, assignor to New Conveyor Company Limited, Birmingham, England

Application November 20, 1950, Serial No. 196,664
In Great Britain November 21, 1949

5 Claims. (Cl. 198—38)

1

This invention relates to conveyors of the kind comprising an overhead track on which are suspended carriers for tilttable trays whereby goods can be transferred from one position to another, the carriers being moved along the track by an endless chain or the like.

It is already known to provide on the carriers, devices for causing the trays to discharge their loads at predetermined positions along the track, these devices consisting in part of a plunger which is operable by contact with ramps on the track and which serves to release a catch associated with the tray.

In the accompanying drawings:

Figure 1 is a side elevation of a portion of a conveyor apparatus for which the invention is required.

Figure 2 is a sectional side elevation.

Figure 3, a sectional front elevation of the mechanism embodying the invention, and

Figures 4 and 5 are similar fragmentary sectional side views showing the mechanism in different positions.

Referring to Figure 1, the overhead track is represented by *a*. From this is suspended a carrier *b* for a tilttable tray *c*. The carrier is movable along the track by a chain *d*. Control of the tray is effected by a mechanism contained in the box *e* mounted on the carrier, which mechanism is fully illustrated by Figures 2 and 3.

Referring to Figures 2 to 5, the box *e* is divided internally by a vertical partition *f* (Figure 3) to form two compartments. In one of the compartments are provided a number of sprockets *g* on which is mounted an endless chain *h*, this being disposed in a zig-zag manner. The spindle *i* of one of the sprockets extends through the partition into the other compartment, and on the part of the spindle in this compartment is secured a ratchet wheel *j*. Also on another spindle *k* in this compartment is secured an actuating lever *m* adapted to receive motion from a plunger *n*. Also to this spindle is secured an arm *o* which is loaded by a spring *p*, and an arm *q* which carries a pawl *r* loaded by a spring *s*. The pawl *r* is adapted to actuate the ratchet wheel *j*, when the lever *m* is depressed by the plunger *n*, and so impart movement to the chain *h*. At the upper end of the plunger *n* (which at its lower end rests on the lever *m*) is arranged a lever *t* (Figure 1) mounted on the carrier *b* and adapted by encountering each in turn of a series of ramps *u* on the conveyor, to depress the plunger and so impart movements to the lever *m* and arm *q* (against the ac-

tion of the spring *p*) for intermittently actuating the ratchet wheel *j* and chain *h*.

Also on the spindle *k* is secured another arm *v* having at its outer end a roller *w* which can engage a recessed shoulder *x* on a catch lever *y* which is pivotally attached to a lever *z* and is loaded by a spring *3* in the manner hereinafter described. The lever *z* is pivoted at *4* and at one end remote from the pivot has attached to it the end of a Bowden cable *5*, through which a tilting movement can be transmitted to the tray *c*.

For actuating the catch lever *y*, there is provided a mechanism comprising an arm *6* secured at one end to a spindle *7*, and connected by a link *8* to an arm *9* pivoted at *10* and provided with a roller *11* in contact with one side of the catch lever *y*. The arm *9* is loaded by the above mentioned spring *3* which acts on the catch lever *y* through this arm and the roller *11*. Also on the arm *6*, there is pivoted at *12* an arm *13* loaded by a spring *14* and provided with a roller *15* in contact with the other side of the catch lever *y*, the angular movement of the arm *13* relatively to the arm *6*, being limited in one direction by a stop *16*.

To the spindle *7* is secured an arm *18* located in the compartment containing the chain, and on the chain is secured at least one tappet *17* adapted to actuate the arm *18*. If desired, a plurality of tappets may be provided on the chain at appropriate distances apart for imparting successive movements to the arm *18* at different stages during the movement of the carrier along the conveyor track.

Figure 2 shows the catch lever *y* (and its associated parts) in condition for actuating the lever *z* and Bowden cable *5* when the plunger *n* is depressed. On depressing the plunger, the lever *m* is moved downwardly against the action of the spring *p* loading the arm *o*. This causes the roller *w* on the arm *v* to engage the shoulder *x* on the catch lever *y*, and impart an upward movement to this lever, causing the lever *z* to be moved for exerting a pull on the cable *5* and so causing the tray to be tilted in a known manner which forms no part of the present invention. At the same time the pawl *r* imparts movement to the ratchet wheel *j* and chain *h*, and so carries the tappet *17* clear of the arm *18*. The spring *3*, by its action of the arm *9* then pulls the catch lever *y* to one side, and rocks the associated arms *6*, *18* to the inoperative position in which the shoulder *x* on the catch lever is out of the path of the roller *w* on the arm *v*, and the arm *18* can again be

actuated when again encountered by the tappet (or the next tappet) on the chain.

Subsequent actuations of the plunger *n* by the ramps on the conveyor have no effect on the catch lever, until the tappet (or the next tappet) comes into action, but each of the successive movements of the plunger causes the pawl *r* to impart a step-by-step movement to the chain through the ratchet wheel.

The length of the chain and the amount of movement given to it by each actuation of the plunger is such that the chain receives one complete sequence of movements while the associated carrier makes one complete circuit of the track on which it is mounted. Consequently when the chain is provided with a single tappet, this effects a single operation of the tray in each circuit, and the position of the tappet *17* on the chain determines the position at which the tray is caused to discharge its load. This position can be varied by means of an external handle *19* on the spindle *i* which carries the ratchet wheel *j*. Alternately when two or more tappets are attached to the chain the latter is actuated at a proportionately slower rate, it being required that the associated tray shall be tilted for the discharge of its load only once during its movement from and to the loading position. Should the circuit have more than one loading position, then the chain is actuated at an appropriate rate so that the load is discharged between any two loading positions.

The mode of action of the control device is as follows:

Starting at a loading position, the chain *h* is pre-set to bring its tappet into such a position that it will become operative when the tray carrier reaches the desired discharge position. The arm *18* now rests against a stop *18¹*, and occupies a position (shown in Figure 5) in the path of the tappet *17*. Also the catch lever *y* occupies its inoperative position in which the shoulder *x* thereon is out of the path of the roller *w* on the arm *v*. Further, the lever *m* is held by the action of the spring *p* on the arm *o* in its uppermost position in which the pawl *r* is clear of the ratchet wheel *j*. During the movement of the carrier along the track the plunger will be actuated successively by each of the ramps which it encounters, and will consequently impart corresponding movements through the pawl and ratchet mechanism to the chain, thereby causing the tappet to be progressively advanced to its operative position. When the station before *17* encounters the arm *18* and moves the latter into the position shown in Figure 2. This causes the catch lever *y* to be moved through the medium of the arms *6*, *13* and the roller *15* to a position in which the shoulder *x* lies in the path of the roller *w* as shown in Figure 2. The next movement of the lever *m* by the plunger *n* serves a dual purpose. It not only causes the pawl *r* to actuate the ratchet wheel *j*, but also causes the catch lever *y* to be lifted for actuating the lever *z*, and thereby causing the tray to be tilted for discharging its load. The various parts now occupy the positions shown in Figure 4. When the lever *m* is released, the various parts automatically revert to the positions shown in Figure 5 under the action of the springs *p*, *3*, and the tray is returned by a spring or counterweight.

To prevent undesired movement of the chain a check lever *20* loaded by a spring *21* may be arranged to engage with any of the sprockets *g*

carrying the chain, and to enable the tray-tilting mechanism to be put out of action, a hand-operable stop may be provided in association with the catch-actuating lever. In the example shown, the stop comprises an arm *22* which is operable by an external handle *23* (Figure 3). The arm *22* is engageable with an arm *24* secured at one end to the arm *13*. When the arm *22* is moved from its out-of-service position (shown in full lines in Figures 4 and 5) to its service position (shown in chain-dotted lines) in which it lies in contact with a roller *25* on the arm *24*, it obstructs the normal movements of the arms *24*, *13*, when the arm *18* is actuated by the chain tappet, and so prevents the catch lever *y* from being moved to its operative position. Any convenient means, such as a plunger *26* on the handle *23* and engageable with either of a pair of recesses in the side of the box *e*, may be provided for securing the handle in either of its two positions.

By this invention the automatic discharge of a loaded tray at any predetermined position on the track can be effected in a very convenient and reliable manner. The invention is not, however, restricted to the example described, as subordinate details of the mechanism may be varied to suit different requirements.

Having thus described my invention what I claim as new and desire to secure by Letters Patent is:

1. A control device for a tiltable tray suspended by a carrier from a conveyor track having a plurality of ramps thereon, comprising the combination of an endless chain provided with at least one tappet, sprockets supporting the chain, means for imparting intermittent movements to the chain, means for tilting the tray, a plunger operable by the ramps on the track, a lever operable by the plunger for actuating the first mentioned means, and a mechanism operable by the chain tappet for engaging the second mentioned means with the said lever.

2. A control device for a tiltable tray suspended from a conveyor track having a plurality of ramps thereon, comprising the combination of an endless chain provided with at least one tappet, sprockets supporting the chain, a ratchet wheel in operative connection with one of the sprockets, a plunger operable by the ramps on the conveyor track, a lever operable by the plunger, a pawl operable by the lever for actuating the ratchet wheel, a lever for tilting the tray, and mechanism movable by the chain tappet into engagement with the plunger-operable lever for transmitting movement therefrom to the tray-tilting lever.

3. A control device as claimed in claim 2, in which the mechanism for transmitting movement from the plunger-operable lever to the tray-tilting lever, comprises a pair of pivotal arms, one of which is operable by the chain-tappet, a link interconnecting the arms, a catch lever pivotally attached to the tray-tilting lever and adapted to receive movement from the plunger-operable lever, an abutment on one of the said arms arranged to act on one side of the catch lever, a second abutment arranged to act on the other side of the catch lever, a spring loaded arm pivotally mounted on the other of the first mentioned arms and carrying the second abutment, and a spring acting on the arm carrying the first mentioned abutment.

4. A control device as claimed in claim 2, hav-

ing in combination with the mechanism for transmitting movement from the plunger-operable lever to the tray-tilting lever, manually operable means for rendering the said mechanism ineffective.

5. A control device as claimed in claim 2, and having in combination with one of the chain sprockets, manually operable means for actuating the chain.
